UNITED STATES PATENT OFFICE.

ALBERT V. RUDD, OF EAST ST. LOUIS, ILLINOIS.

RAILWAY-TIE MECHANISM.

Application filed January 14, 1926. Serial No. 81,148.

My invention relates to improvements in railway tie mechanism and has for its object to provide a tie capable of receiving, and detachably holding, rails of various 5 weights and various widths of tread. The structure of my invention embodies the tie itself, and cooperating elements which insure the rail being held securely upon the tie and being released by a definite and simple operation of the holding elements. Other advantages of my invention will appear from the following description.

Drawings.

15 In the drawings—

Fig. 1 is a longitudinal view of the tie embodying my invention partly in section.

Fig. 2 is a top plan view of a portion of the tie, with a fragment of the rail in place.

20 Fig. 3 is a top plan view of a fragment of the tie, the holding elements being removed.

Fig. 4 is a perspective view of the locking spike employed in said tie construction.

25 Fig. 5 is a perspective view of the spike-lock.

Fig. 6 is a perspective view of the wedge employed in securing said lock in place.

Description.

30 The tie A is preferably cast and comprises a top wall 7 and bottom wall 8, vertical transverse walls 9 and lock-guides 10. The rail B being seated in place upon the tie A, the spike C having the head 11 and locking 35 projections 12—12, is dropped through the cruciform slot 13 into top wall 7 until the lower face of the head 11 is in contact with the top face of the base 14, and the spike 40 lies vertically with its straight face resting against the adjacent face of the transverse tie-wall 9 as shown in Fig. 1.

Thereupon the locking element D is 45 dropped into place, as shown in Fig. 1, with its cross-bar 15 resting beneath the wall 7

as shown in Figs. 1 and 2, and its jaws 16—16 engaging with the locking projections 12—12 in the manner shown in Fig. 1. Thereupon the locking wedge E, preferably constructed as shown in Fig. 6, is 50 dropped into the position shown in Fig. 1, with its tooth 17 in engagement with the notch 18, which notch 18 is formed upon the rear face of the lock D. The wedge E has the flat upper face 18^a, which serves to 55 receive the blows of a sledge or other hammering implement, to seat the wedge E firmly in the position shown in Fig. 1. The wedge E has a series of parallel perforations 19, and when the wedge E is seated 60 in the desired position it is locked in such position by means of a pin 20, passing through the ears 21—21 formed on the upper wall 7 of the tie A, and through one 65 of the perforations 19.

In releasing the rail from the tie for the purposes of replacement or repair, the wedge E is released from its locked position by the removal of the pin 20; the wedge E is then withdrawn from its position within 70 the tie A; the spike-lock D is then removed from engagement with the spike C; and the spike C is then withdrawn from its seat within the tie A.

The foregoing description and the drawings exhibit the preferred form of my invention, in which various structural changes may be made without departure from my actual invention as defined in the claim hereof.

I claim:—

In a railway tie mechanism, in combination with a tie, a spike having locking projections; a lock arranged to engage said projections; and a wedge arranged to hold 85 said lock in engagement with said spike.

In testimony whereof I have hereunto affixed my signature.

ALBERT V. RUDD.
